GARMENT HANGER

Aaron Levinson, Bronx, N. Y., assignor to
Augusta Leverson, Brooklyn, N. Y.

Application February 28, 1947, Serial No. 731,626

1 Claim. (Cl. 223—92)

1

This invention relates to garment hangers.

Broadly, it is an object of my invention to provide a garment hanger with movable and adjustable shoulder pieces to accommodate coats, jackets and the like of different widths.

More particularly, it is an object of my invention to provide an improved garment hanger having movable shoulder pieces which slide upon a dovetail groove and which may be fixed after adjustment of the shoulder pieces.

A further object is to provide a garment hanger, the shoulder portions of which are arcuate and end along substantially a straight line so that the garment, such as a jacket or coat will hang properly without deforming the garment and aiding it to fall in its original lines thus saving pressing and prolonging the life of the garment.

Still a further object is to provide a light yet durable garment hanger at a reasonable cost.

For a fuller understanding of the nature and objects of the invention, reference is had to the following detailed description in connection with the accompanying drawing, in which:

Fig. 1 is a front elevation of the garment hanger, partly broken away to show the construction of the shoulder member.

Fig. 2 is an enlarged end elevation of the shoulder member and hanger, the upper portion of the hanger being partly broken away.

Fig. 3 is an enlarged top view of the shoulder member.

Fig. 4 is an enlarged end view from the narrow end of the shoulder member.

Fig. 5 is an enlarged sectional view taken along line 5—5 of Fig. 1.

Fig. 6 is an enlarged front elevation of one end of the hanger showing the groove.

Referring to the drawing, numeral 10 represents a garment hanger which may be made of wood, metal, plastic or the like material and comprising oppositely disposed arms 11 and 12 which slope upwardly towards the central portion forming the collar supporting portion 13. Although I have not shown a cross bar running between the outer lower ends of the arms 11 and 12 for supporting a folded garment, such as trousers, it is well known in the art to have such cross bar which may be added if desired. A hook 14 preferably made of wire passes through a central vertical channel so that the entire garment hanger 10 may be suspended from any suitable support.

The ends of arms 11 and 12 along the top portion 15 are along a flat or straight plane and have a dovetail groove 16 on opposite sides of the upper side portions, creating a dovetail central

portion 17 as shown in Figs. 2 and 5. A nut 18 is embedded within the dovetail portion 17 to receive a screw 19 which passes through a hole in the end and communicates with the hole in the nut 18. Of course, if the arms 11 and 12 are made of metal or plastic, the thread could be made in the material itself thus eliminating the nut 18.

At each end of arms 11 and 12, I have provided adjustable shoulder members or supports 20 formed with a convex outer portion 21 and having a straight extreme end 22, and tapers inwardly and upwardly merging into a rounded end 23. The shoulder members 20 are provided with a dovetail straight groove 24 along its medial line adapted to slidably fit upon the dovetail portion 17. A series of depressions 25 are spaced along the upper medial line of groove 24 to receive the ends of screws 19 to more easily prevent shifting or movement of the shoulder members 20 when screws 19 are tightened. Since the shoulder members 20 cannot move upward because of the dovetail construction, the depressions 25 may be eliminated since the ends of screws 19 when tightened will frictionally hold the shoulder pieces 26 from moving or shifting.

In order to assemble the hanger, the shoulder members 20 are slid with the rounded ends 23 first onto the ends of arms 11 and 12 by inserting the dovetail portion 17 into the groove 24. The screws 19 are in lower position, that is, with the ends below the top portion 15. When the shoulder members are in the desired position, screws 19 are tightened against the shoulder members thus preventing them from shifting.

In garment hangers which have no movable or adjustable ends it can accommodate but one size. If the shoulders of the garment are wider than the ends of the hanger arms the shoulders sag and the garment loses its shape. Furthermore, the usual garment hanger has narrow ends giving inadequate support to the shoulders causing them to sag so that the jacket or garment loses its shape and causes a wrinkled appearance. My wide and outwardly tapered arcuate convex shaped shoulder members give adequate support to the shoulders of the garment and when the shoulder members are properly adjusted the sleeves of the garment fall or hang properly maintaining the proper shape of the shoulders, sleeves and consequently the rest of the garment. By thus hanging overnight the daily wrinkles straighten themselves out giving the garment a neat and tidy appearance. By avoiding frequent pressing the life of the garment is thus prolonged.

The slight ridge created by ends 23 serves to

prevent the garment from slipping. For traveling the shoulder portions 20 can be easily removed and the hanger packed to occupy a minimum of space. The concavo-convex shoulder members can be nested within the other and packed within the bag or trunk wherever space is available, especially in corners. For shipping and storage such saving of space is also of great value.

It is obvious that various changes and modifications may be made in the details of construction and arrangement of parts without departing from the general spirit of the invention.

I claim:

A garment hanger having oppositely disposed arms sloping into a collar supporting portion, a hook attached to said collar supporting portion, the upper outer end portion of said arms having a straight dovetailed portion, screws passing upwardly through said arms and said dovetailed portions, adjustable shoulder members, said mem- 20

bers having outer convex surfaces, a straight extreme end and sides tapering towards the end opposite said straight ends, a straight dovetailed groove along the bottom medial line of each of said members, said members being slidably adapted to ride upon said dovetailed portion of said arms and a number of spaced depressions in the bottom of said dovetailed grooves whereby tightening said screws prevent said shoulder members from shifting.
